GUN

William Summerbell, Watervliet, N. Y.

Application July 13, 1939, Serial No. 284,255

4 Claims. (Cl. 42—70)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a gun.

In guns of the type shown in Patent No. 1,144,285 of June 22, 1915, a breech block operating on the "blow-back" principle is arrested at the end of recoil and then released by a trigger to advance a cartridge into the gun barrel.

The purpose of this invention is to provide a simple and efficient sear and trigger mechanism for a breech block and to provide means for opposing actuation of the trigger to release the block in the event that a cartridge is already in the barrel. This latter provision is particularly necessary in a gun using fused ammunition.

The specific nature of the invention as well as other objects and advantages thereof will clearly appear from a description of a preferred embodiment as shown in the accompanying drawings in which:

Fig. 1 is a plan view of the breech end of a gun with parts removed and parts in section showing the breech block in battery and the trigger in normal position.

Figs. 2 and 3 are sectional views on the corresponding lines of Fig. 1.

Fig. 4 is a view in side elevation of the rear end of the gun frame.

Fig. 5 is a sectional view on the line 5—5 of Fig. 1.

Fig. 6 is a sectional view on the line 6—6 of Fig. 5.

Referring to the drawings by characters of reference there is shown a gun frame A, a barrel B fixed to the frame, and a reciprocable breech block C of the blow-back type. The means for checking the breech block in recoil and returning it to firing position or into battery forms no part of this invention and is not shown. The breech block is arranged to advance a round of ammunition D into the chamber b of the barrel and to fire the round before the block reaches the rear face of the barrel so that the gas pressure is first utilized to arrest the forward motion of the block before acting to drive it rearwardly in recoil. The lower face of the breech block is formed with a lug 5 having a cam face 6 inclined to the longitudinal axis of the block and a shoulder 7 disposed transversely of the axis of the block.

The gun frame A, as shown in Fig. 2 is formed from a cylindrical tube that is partially cut away

5 to receive spaced parallel plates 8—8 for supporting and guiding the breech block. A trigger housing 9 is attached by means of screws 10 to the under side of the lower plate 8 adjacent its rear extremity.

A sear 11 mounted in the housing 9 on a pivot pin 12 has a rearwardly extending arm 13, a forwardly extending arm 14, and a laterally extending arm 15. An upright stud 16 on the arm 13 extends through an opening 17 in the lower plate 8 and into the path of movement of the lug 5 on the breech block. A depending stud 18 on the lateral arm 15 is disposed in the path of movement of the toe 19 of a trigger 20.

10 The trigger 20 is positioned transversely of the housing 9, underlies the rear arm 13 of the sear, and is mounted on a pivot pin 21 threadedly secured in the housing. The shank of the trigger passes through an opening 22 in a safety bolt 23 which is slidably mounted in the housing. The finger piece of the trigger projects laterally from the housing in front of a rigid handle 24 on the housing.

15 The trigger 20 is positioned transversely of the housing 9, underlies the rear arm 13 of the sear, and is mounted on a pivot pin 21 threadedly secured in the housing. The shank of the trigger passes through an opening 22 in a safety bolt 23 which is slidably mounted in the housing. The finger piece of the trigger projects laterally from the housing in front of a rigid handle 24 on the housing.

20 The trigger 20 is positioned transversely of the housing 9, underlies the rear arm 13 of the sear, and is mounted on a pivot pin 21 threadedly secured in the housing. The shank of the trigger passes through an opening 22 in a safety bolt 23 which is slidably mounted in the housing. The finger piece of the trigger projects laterally from the housing in front of a rigid handle 24 on the housing.

25 A safety latch 25 slidably mounted in the handle and normally urged outwardly against a stop shoulder 26 by means of a spring 27 has a solid inner end projecting into the path of movement of the bolt 23. An aperture 28 is formed in the latch adjacent the solid inner end so that when the latch is moved towards the gun frame against the action of the spring, the aperture will be in line with the bolt 23 to enable the bolt to be moved rearwardly under impulse from the trigger.

30 A plunger 29 disposed transversely in the housing 9 is held by a spring 30 against the forwardly extending arm 14 of the sear 11. The plunger normally maintains the sear in a position with the upright stud 16 in the path of the lug 5 of the breech block and with the depending stud 18 in rearmost position whereby it acts on the toe 19 of the trigger 20 to hold the projecting finger piece of the trigger in foremost position. Such positioning of the trigger insures the forward displacement of the safety bolt 23 with the safety latch 25 automatically moved or held in a position to oppose retraction of the bolt and movement of the trigger.

35 The gun barrel B (Fig. 6) is provided with a counterbored radial passage 31 for housing a plunger 32 whose inner end is normally protruded into the cartridge chamber b by means of a spring 33 acting on a collar 34. The spring is seated on a plug 35 threaded into the barrel to close the passage 31 and the plug is provided

40 45 50 55

The gun barrel B (Fig. 6) is provided with a counterbored radial passage 31 for housing a plunger 32 whose inner end is normally protruded into the cartridge chamber b by means of a spring 33 acting on a collar 34. The spring is seated on a plug 35 threaded into the barrel to close the passage 31 and the plug is provided

with an aperture 36 to receive the outer end of the plunger which is normally flush with the outer face of the plug.

A housing 37 mounted in a recess in the outer side of the gun frame A and secured in place by a screw 38 is provided with a slot 39 which is aligned with the plunger 32. A tubular slide 40 in the housing is threaded to a rod 41 which protrudes from the rear end of the housing and carries a coupling member 42 which is attached to an operating rod 43 pivotally connected to the trigger 20. The slide is formed with a diametral slot 44 for receiving a latch 45 which is mounted adjacent its forward end on a pivot pin 46. A rearwardly extending finger 47 on the latch extends into the slot 39 in the housing and its rear end is normally positioned forwardly of the plunger 32. The latch is maintained in this position by means of a plunger 48 and plunger spring 49 housed in the slide.

The elements of the trigger group, when at rest, are normally in the position shown in Fig. 1. When the breech block C is retracted the cam face 6 of the lug 5 strikes the upright stud 16 on the sear and causes the sear to rotate about its pivot and compress the spring 30. When the lug 5 clears the stud 16, the sear is immediately restored by spring 30 to interpose the stud 16 in the path of the shoulder 7 and thereby hold the breech block in the retracted or loading position.

When it is desired to release the breech block so that it may advance a cartridge into the barrel, the operator grasps the rigid handle 24 and the trigger 20, employs his thumb to move the safety latch 25 and align the aperture 28 with the safety bolt 23, and then contracts his fingers to pull the trigger 20. The toe 19 of the trigger acts on the depending stud 18 to move the sear and release the breech block.

Upon retraction of the trigger the slide 40 and latch 45 are also moved rearwardly and the latch is positioned in line with the plunger 32. As the carriage advanced by the breech block enters the chamber b of the barrel the plunger 32 is moved outwardly and displaces the latch. Upon release of the trigger the slide returns to its normal forward position and moves the latch clear of the plunger 32 so that the spring pressed plunger 48-49 may restore it to its normal position. Under the condition where a cartridge is in the chamber and the breech block held in the loading position by the sear, the plunger 32 is ex-

truded into the path of the latch and will thereby prevent retraction of the trigger which would release the breech block to advance a second cartridge towards the already loaded chamber b.

5 I claim:

1. In a gun, a frame, a breech block reciprocal-
10 ble in the frame, a lug on the breech block, a housing attached to the frame, a sear pivotally mounted in the housing transversely thereof and
15 formed with a forwardly extending arm, a rear-
wardly extending arm and a laterally extending
15 arm, a stud on the rearward arm extending into
the frame for engagement with the lug on the
breech block, a downwardly extending stud on
20 the lateral arm, a spring acting on the forward
arm, a trigger pivotally mounted transversely in
the housing and having a toe engaging the stud
on the lateral arm of the sear, a safety bolt
25 in the housing operatively engaged by the trigger,
20 and a manually operable latch normally oppos-
ing movement of the bolt.

2. The invention of claim 1 characterized in
that the relative position of the trigger latch and
25 trigger is such that they may be manually oper-
ated substantially simultaneously with one hand
to release the breech block.

3. In a gun, a frame, a breech block reciprocal-
30 ble in the frame, a housing attached to the
frame, a sear pivoted in the housing for move-
35 ment in a plane parallel to the axis of reciproca-
tion of the breech block, a stud on the sear ex-
tending into the frame in a direction transverse
35 to the plane of sear movement, a lug on the
breech block adopted to be engaged by the stud,
means normally holding the sear in position to
engage the breech block, and a trigger pivotally
40 mounted in the housing, in a plane parallel and
adjacent to the sear and overlapping the sear
and having operative engagement therewith, to
move the sear and be moved thereby.

4. In a gun, a frame, a housing attached to
the frame and including a projecting handle, a
trigger pivotally mounted in the housing for
swinging movement toward the handle, a safety
45 bolt in the housing and connected to the trigger
for reciprocation in a direction transverse to the
handle upon movement of the trigger, a latch
mounted in the handle for sliding movement
50 along the axis thereof and normally opposing
movement of the bolt, and a thumbpiece on the
latch for moving the latch to free the bolt.

WILLIAM SUMMERBELL.
